US0D1075405S

(12) **United States Design Patent** (10) **Patent No.:** **US D1,075,405 S**
(45) **Date of Patent:** **** May 20, 2025**

(54) **COMBUSTION CONTAINER PANEL**

(71) Applicant: **Firebox Outdoors LLP**, Moroni, UT (US)

(72) Inventor: **Steven S. DeSpain**, Moroni, UT (US)

(73) Assignee: **Firebox Outdoors LLP**, Moroni, UT (US)

(**) Term: **15 Years**

(21) Appl. No.: **29/870,502**

(22) Filed: **Jan. 27, 2023**

CLAIM

The ornamental design for a combustion container panel as shown and described herein.

DESCRIPTION

FIG. 1 is a front perspective view of a combustion container panel;

FIG. 2 is a rear perspective view of the combustion container panel;

FIG. 3 is a front view of the combustion container panel;

FIG. 4 is a back view of the combustion container panel;

FIG. 5 is a side view of the combustion container panel;

FIG. 6 is another side view of the combustion container panel;

FIG. 7 is a top view of the combustion container panel; and,

FIG. 8 is a bottom view of the combustion container panel.

The dashed broken lines show portions of the combustion container panel and form no part of the claimed design. The dot-dot-dash broken lines illustrate the bound of the claimed design and form no part of the claimed design.

1 Claim, 6 Drawing Sheets
